(57) **CLAIM**

The ornamental design for a cooking apparatus, as shown and described.

DESCRIPTION

The file of this patent contains at least one drawing executed in color. Copies of this patent with color drawings will be provided by the Office upon request and payment of the necessary fee.

FIG. 1 is a front perspective view of a first embodiment of a cooking apparatus in accordance with the subject disclosure.

FIG. 2 is a right side view of the cooking apparatus of FIG. 1.

FIG. 3 is a left side view of the cooking apparatus of FIG. 1.

FIG. 4 is a front view of the cooking apparatus of FIG. 1.

FIG. 5 is a rear view of the cooking apparatus of FIG. 1.

FIG. 6 is a top view of the cooking apparatus of FIG. 1.

FIG. 7 is a bottom view of the cooking apparatus of FIG. 1.

FIG. 8 is a top perspective view of the cooking apparatus of FIG. 1; and,

FIG. 9 is a bottom perspective view of the cooking apparatus of FIG. 1.
